UNITED STATES PATENT OFFICE.

LESTER E. VAN HISE AND JAMES V. BALDWIN, OF LOS ANGELES, CALIFORNIA.

FLUID ELEVATING AND FEEDING MEANS.

Application filed April 10, 1922. Serial No. 551,244.

To all whom it may concern:

Be it known that we, LESTER E. VAN HISE and JAMES V. BALDWIN, citizens of the United States, residing at Los Angeles, in the 5 county of Los Angeles and State of California, have jointly invented new and useful Improvements in Fluid Elevating and Feeding Means, of which the following is a specification.

10 This invention relates to fluid elevating and feeding means, and particularly to a device which is adaptable for use in motor vehicles in that it may be used in an embodiment to be described for causing flow of 15 gasoline from a fluid supply tank to a carburetor, without the necessity of using any extraneous means such as the well-known vacuum system.

The invention in one of its embodiments 20 includes a pumping chamber arranged within the exhaust manifold of a vehicle and into which gasoline is drawn. Gasoline flowing into the pumping chamber is vaporized by the heat from the exhaust gases of 25 the manifold and this vapor tends to force gasoline to a fluid reservoir; the operation being continuous or intermittent, tends to actively pump gasoline, and the gasoline so pumped is eventually conducted to the carburetor well.

30 This invention is an improvement over our co-pending application for patent for fluid elevating and feeding means, filed September 3, 1921 in the United States Patent Office, Serial No. 498,434. This invention has for its object the provision of an 35 improved fluid elevating and feeding means which will be superior in point of relative simplicity and inexpensiveness, taken in 40 conjunction with utility, durability and general efficiency and serviceability.

In the drawing:

45 Figure 1 illustrates an adaptation of the invention incorporated in conjunction with the power unit of a motor vehicle; and

50 Figure 2 is a fragmentary cross sectional view of the improved fluid elevating and feeding means in its entirety, the same being associated with a well member and the various elements to make an entity.

55 Corresponding parts in both figures are designated by the same reference characters.

Referring with particularity to the drawing, A designates a motor vehicle incorporating the usual engine 1 having a carburetor 55 as shown in dotted lines at 2, with a liquid

supply tank 3 and an exhaust manifold 4 associated with the engine member 1. The remaining features of the motor vehicle will not be taken up in detail. The fluid elevating and feeding means is designated in its entirety by B, and the said means operates in conjunction with a reservoir member C. The means B has an energizing or pumping element X which includes a tubular well 5 closed at one end and having a stud 6 projecting from the base member thereof; and the well is also provided with screw threads 7 adjacent the open mouth thereof. Thus the member B has the characteristics of a bottle since it is closed at one end and open at the other and may therefore be conveniently termed a pumping bottle even though it is of uniform diameter throughout. The said member 5 is adapted to pass through an opening 8 in the exhaust manifold 4 and held positioned within said exhaust manifold 4 by the stud 6 projecting through a small perforation in the manifold 4, there being a nut 9 screw-threaded upon 80 the stud and in engagement with a portion of the periphery of the manifold 4. Likewise the member 5 is provided with an annular flange 10 for maintaining the member 5 in position. An additional function of 85 the flange consists in sealing the opening surrounding the point of admittance of the member 5 within the manifold 4. A T-head 11 has a portion thereof as 12 screw-threaded upon the threads 7 of the member 90 5 with further conduits 13 and 14 screw-threaded within the horizontal portion or the head portion of the T-head, as shown at 15 and 16. A conduit 17 connects with the source of liquid supply or tank 3 with 95 a terminal of a valve member a, the pipe 13 connecting with the other terminal of said valve. The pipe or conduit 14 connects with a valve member b, which valve member is associated with the well or reservoir C. The reservoir C may comprise a cylindrical tank 18 having top and base members 19 and 20 provided with bracketed portions 21 and 22, whereby the reservoir C as an entirety may be attached to the 100 frame or some portion of the vehicle structure, as shown at 23. Rods 24 may extend between the top and base members and securely hold the member 18 in position therebetween. What may be termed an overflow 105 pipe 25 extends within the reservoir C and connects by a return pipe with the tank 3

A conduit 26 extends through the base member 20 and leads to the carburetor 2. As illustrated, the reservoir C is preferably located above the carburetor well. This is in order that there may be a gravity feed of liquid from the reservoir to the carburetor. The valves a and b are more or less identical in construction, and for that reason only one of said valves will be described in detail, the same letters of reference applying to the other valve.

Referring to the valve a, said valve is provided with a chambered body member 27 and with a reduced annular end 28 provided with external screw threads 29; the annular opening in said reduced portion 28 leading directly to the chambered portion of the body. An annular cap nut 30 is screw-threaded upon the threads 29 and said cap nut holds in position one end of the pipe 13, the said pipe being provided with an annular flange 31 to accomplish said function. An end of the member 27 is relieved and internally screw-threaded as shown at 32, and a flanged annular nut or nipple 33 has a portion thereof screw-threaded upon the part 32, while a second portion thereof is provided with screw threads as at 34 for reception of an annular cap nut 35. Said cap nut confines a flanged end 36 of the conduit 17. The nut 33 is provided with a valve seat 37, and a ball member 38 is normally seated thereon, being maintained in position by a compression spring 39 within the chamber of the member 27. The valve a may be placed anywhere in the line 17, preferably, however, beyond the point of connection of the overflow pipe 25 with the conduit 17, and the valve b may be associated with the cap or top 19 of the well C. The well C is provided with the usual vent opening and plug as illustrated at 40.

The chief improvement of this invention consists in the introduction within the member 5 of a tubular member c, said tubular member being open at an end thereof as at 41 and closed at the opposite end by a plug 42. The said member c is held in position spaced from the interior of the member 5 by a screw member 43 projecting through the T-head and in screw-threaded engagement with the plug 42. It is to be noted upon reference to the drawing that the energizer or pumping means x may be placed in a vertical position within the exhaust manifold and that a portion thereof extends outwardly from the manifold. The result accomplished by the introduction of the means c is best described by stating the operation of the device as a whole.

If liquid is conducted from the tank 3 through the pipe 17 and allowed to flow within the member 5, the liquid will rise a certain distance within the member c until

the pressure within the same equalizes the pressure of liquid without and prevents a further rising of said liquid. If the engine is started the heated gases passing through the exhaust manifold will tend to heat the lower zone of the member 5, which heat will be communicated to the liquid within the member 5. This of course causes an expansion of the liquid within the member 5, and as the member c will likewise be heated any gas confined within it will also tend to expand. Obviously the liquid will tend to gasify and exert a pressure within the member 5 and the member c. This pressure will become great enough to force the liquid out of the member c and force any liquid within the member 5 back toward the T-head 11. The check valve b will prevent the gasoline or other liquid from flowing back through the pipe 13 and as a consequence the gasoline will be forced through the pipe 14 past the check valve b and into the reservoir C. This forcing of the gasoline into the pipe 14 will cause a reduction of pressure tending toward an equilibrium, and likewise tend to create a vacuum due to the condensation of the vapor in the top half of the member 5 when in contact with the cooler surfaces and liquid which will aid in the drawing of liquid from the source of supply. We will thus have an expansion of the liquid by a gasification thereof, which expansion will cause a pressure forcing gasoline to the well member, followed by a contraction of the gas which will draw more liquid into the pump chamber. It is to be particularly noted that the arrangement of the member c within the member 5 allows a portion thereof to be above the normal influence of the heated gases passing through the intake manifold.

4. Likewise by extending the member 5 outwardly from the exhaust manifold we have what may be termed a condensation chamber. In other words, one portion of the member 5, as well as the member c, will be subjected to heat influence, while a second portion will tend to be cool. The member c performs many useful functions in that it restricts the area in the pump chamber at the zone of direct heat influence. It is essential that the area that may exist within the annular space between the members c and 5 should be small in proportion to the condensation space immediately above the same. In other words, the condensation area must be greater than the vaporization area in order to create the necessary pressure and vacuum to cause flow of gasoline or other liquid from its source of supply to the tank C. Another important function of the member c resides in the fact that it is so arranged that it permits of adjustment of pumping speed; it increases the cooling area, aids in lowering pressure for

a given amount of liquid fuel vaporized and likewise cushions the pumping action of the device, as it is to be noted that the open mouth of the member *c* is pointed 5 toward the base of the member *5* and as it heats, any gas confined in its upper extremity is forced downwardly exerting a pressure upon any liquid within the same and within the well *5*. This pressure of course 10 fluctuates and any liquid entering the well through the pipe *13* being cool contacts with the vapor passing through the annular space between the members *5* and *c* tending to condense said vapor, reduce the pressure thereof, and likewise form a vacuum aiding in the drawing of more liquid 15 through the pipe *13* from its source of supply.

Particular attention is drawn to the fact 20 that the overflow pipe *25* passes directly to and connects with the tank *3*. A member *44* is placed on the line *25*, the said member *44* being provided with radiating vanes so as to cool any liquid flowing through said pipe. 25 We likewise provide a member *44* for the pipe line *17*. Thus as liquid, such as gasoline, is pumped into the reservoir *C* the overflow of liquid passing through the pipe *25* is cooled. Quite obviously any liquid such as 30 gasoline pumped to the reservoir *C* would be warm or hot, as the case might be, and it is desirable to remove as much heat from this liquid or gasoline as possible before passing same to the carburetor *2*. Obviously, 35 liquid such as gasoline flowing through the pipe *25* to the tank *3*, then from the tank *3* through the line *17* connecting with the pump, will tend to remove heat from said liquid. Attention is directed to the fact 40 that a turning of the screw member *43* will raise or lower the element *c* so that a variation in the pumping action may be effected. If the means *c* were raised a smaller area thereof would be subjected to direct heat 45 influence and vice versa for a movement in the opposite direction. We have by the construction illustrated provided a system in which the heat content of the liquid flowing within the pipes may be directly regulated.

50 It is obvious that various changes and modifications may be made in departure from the particular description and showing of the accompanying drawing in adapting the invention to varying conditions and requirements of use and service, without departing from the true spirit of the invention and the scope of the appended claims.

Having thus disclosed our invention, we claim and desire to secure by Letters Patent: 55 1. In a liquid-fuel pumping apparatus of the class described, the combination with a source of liquid-fuel supply and the exhaust manifold of an engine, of a pumping bottle having its closed end disposed within said

connections communicating with the upper end of the bottle, and a tubular shell closed at one end and open at the other and arranged within the bottle to provide a liquid sealed vapor chamber when the bottle is supplied 70 with liquid-fuel.

2. In a liquid-fuel pumping apparatus of the class described, the combination with a source of liquid-fuel supply and the exhaust manifold of an engine, of a pumping bottle 75 having its closed end disposed within said manifold, a cap fitted to the open end of said bottle, valved intake and discharge connections communicating with said cap, and a tubular shell closed at one end and open 80 at the other and arranged within the bottle to provide a liquid sealed vapor chamber when the bottle is supplied with liquid-fuel.

3. In a liquid-fuel pumping apparatus of the class described, the combination with a source of liquid-fuel supply and the exhaust manifold of an engine, of a pumping bottle having its closed end disposed within said manifold, a cap fitted to the open end of said bottle, valved intake and discharge connections 85 communicating with said cap, and a tubular shell carried by said cap and suspended within the bottle to provide a relatively constricted space between the shell and the bottle and also provide a liquid sealed vapor chamber when the bottle is supplied 90 with liquid-fuel.

4. In a liquid-fuel pumping apparatus of the class described, the combination with a source of liquid-fuel supply and the exhaust manifold of an engine, of a pumping bottle having its closed end disposed within said manifold, a cap fitted to the open end of said bottle, valved intake and discharge connections 100 communicating with said cap, and a tubular shell adjustably carried by said cap and suspended within the bottle to provide a relatively constricted space between the shell and the bottle and also provide a liquid sealed vapor chamber when the bottle is supplied 105 with liquid-fuel.

5. A thermal pump of the class described including a tubular receptacle having valved intake and discharge connections, and a tubular shell open at one end and closed at the other and arranged within the tubular receptacle to provide a relatively constricted passage between the shell and the receptacle and to also provide a liquid sealed vapor chamber within the shell when the receptacle is supplied 115 with fluid.

6. In a fluid feeding device of the class described, the combination with a source of heat and a source of fluid supply, a pumping bottle having its closed end disposed 120 within the zone of heat influence, valved intake and discharge connections communicating with the open end of the bottle, and a tubular pumping shell arranged within the bottle and having a closed end and an open 125

end, the said open end being disposed toward the bottom of the bottle and being sealed by liquid within the bottom thereby cooperating with the said closed end to provide a sealed vapor chamber adapted to discharge toward the bottom of the bottle when the effect of heat on the bottom of said bottle expands the vapor in said vapor chamber.

7. A fuel pumping apparatus including the combination with the exhaust manifold of an engine, a pumping bottle arranged partly within the manifold, a fuel storage tank, a feed pipe leading from said storage tank to the open end of the bottle, a check valve in said feed pipe, a discharge pipe also communicating with the open end of

the bottle, a check valve in said discharge line, a receiving well for holding fuel expelled from said discharge line, a connection between the receiving well and the carburetor, an overflow pipe line between the receiving well and the storage tank, and cooling vanes arranged on said feed and overflow pipe lines.

In testimony whereof, we have signed our 25 names to this specification in the presence of two subscribing witnesses.
